(57) CLAIM

The ornamental design for a pet treat, as shown and described.

DESCRIPTION

FIG. 1 is a front perspective view of a pet treat showing our new design;

FIG. 2 is a back perspective of the design shown in FIG. 1;

FIG. 3 is a front view of the design shown in FIG. 1;

FIG. 4 is a back view of the design shown in FIG. 1;

FIG. 5 is a left side view of the design shown in FIG. 1;

FIG. 6 is a right side view of the design shown in FIG. 1;

FIG. 7 is a top view of the design shown in FIG. 1; and,

FIG. 8 is a bottom view of the design shown in FIG. 1.

The broken lines in the drawings illustrate portions of the pet treat which form no part of the claimed design.

1 Claim, 4 Drawing Sheets
